MICROPHONE CASING

Maurice M. Palo, Conneaut, Ohio, assignor to The Astatic Corporation, Conneaut, Ohio, a corporation of Ohio

Application April 1, 1954, Serial No. 29,809

Term of patent 7 years

(Cl. D26—14)

Figures 2, 3, 4, and 5 are top, front, bottom, and side views respectively, of the microphone casing shown in Figure 1.

The dominant features of my design reside in the portions shown in full lines.

I claim:

The ornamental design for a microphone casing, as shown and described.
